PROJECTILE PROPELLING APPARATUS FOR USE IN
HIGH TEMPERATURE ENVIRONMENT
Filed July 2, 1962

FIG. 1

ing through both plate 30 and annulus 31 are preferably such as to form a fit of controlled tightness upon the bullet 26. The annulus 31 and the plate 30 form restraining means from which the bullet is dislodged only upon the building up of sufficient pressure within the firing chamber by deflagration of the propellant charge.

A cylindrical firing chamber is shown at 40, formed by a bore 41 of inside diameter reduced relative to that of the threaded barrel opening 16 but uniform throughout its length and extending concentrically inward from the innermost end of the barrel opening 16. The firing charge within firing chamber 40 is made up of secondary high explosive body 45 in consolidated or pelletized tubular form and having an opening or passage 46 extending centrally therethrough from end to end. The body 45 is shown as surrounded by a sleeve or shell 47 which is more fully described in relation to the other parts of the structure in the aforementioned Porter patent.

In the embodiment of the invention described, actuation of the body 45 is accomplished by means of igniter 44 which is preferably a cup-like head member, containing a combustible low explosive powder such as black powder and an electrical resistance element therein (not shown). Construction of this particular type of igniter is disclosed in U.S. Patent 2,649,736 to Robert A. Phillips and the actuation of such igniter is accomplished by means described and illustrated in the aforementioned Porter patent.

In accordance with this invention the body 45 comprises a secondary high explosive, for example, trimethyl-1-enetrinitramine, commonly referred to as "cyclonite" or "RDX." Heretofore, bullet perforating guns have uniformly utilized a low explosive such as double base powder. The use of the latter type of explosive prevented bullet perforators from being operated at temperatures much in excess of 300° F. This is because such low or deflagrating explosives ignite spontaneously when maintained at temperatures above 300° F. for the period of time that a perforating assembly is normally in the oil well. Cyclonite, on the other hand, is capable of withstanding temperatures on the order of 350° F. for 24 hours without self-ignition and to withstand temperatures as high as 390° F. for the length of time normally required to run the perforator in the high temperature portion of an oil well.

An important feature of the invention is the use of a low explosive or deflagrating initiator in combination with a secondary high explosive of the type conventionally detonated. It is important to prevent detonation of the explosive body 45 otherwise the gun body 12 will be split and the tool ruined. In accordance with this invention, it has been found that secondary high explosives may be ignited in a deflagrating rather than a detonating manner by use of a low explosive as an initiator. Low explosives, such as black powder or smokeless powder (which themselves are deflagrated by heat) have been found to initiate deflagration of secondary high explosives such as cyclonite, whereas the use of conventional detonators or boosters of the so-called primary high explosive type (lead azide, mercury fulminate etc.) would cause the same secondary high explosive to detonate.

Although black powder is a preferred actuating means for this invention, it will be understood that other conventional low explosives may be employed, for example, a commercially available mixture of boron chromate and barium chromate. Primary high explosives of the type ignited by impact, such as lead azide, should not be used as initiators because they will cause detonation of the secondary high explosive body and damage or destroy the gun.

The mode of actuation of the secondary high explosive is determinative of whether its combustion will initially follow the deflagrating rather than the detonating course. Because detonation of body 45 must be avoided to prevent damage to the perforating tool, it is also important

to keep the ambient pressure around the tool, it is also important to keep the ambient pressure around the explosive body from reaching a level at which there is a transition from explosive deflagration to detonation. For cyclonite this pressure is in the order of 20,000 kilograms per square centimeter. It has been found that for most secondary high explosives useful as propellants excessive pressure build-up is avoided by fitting the bullet 26 into the restraining members 30 and 31 by means of a tight press fit. As explained in the aforementioned Porter patent, it is necessary to restrain the movement of the bullet 26 until combustion of the propellant explosive has been substantially completed so that its propelling force can be efficiently utilized and sufficient kinetic energy supplied to the projectile to enable it to accomplish the required perforation. It has been found that the tight press fit which accomplishes this desirable result also permits movement of the bullet 26 from the firing chamber before the pressure therein can be built up to a value at which transition from deflagration to detonation takes place.

It will be appreciated that other secondary high explosives besides cyclonite may be used in this invention and that such explosives have different critical pressures at which detonation occurs. For such other detonating explosives, obviously, different restraining forces on the bullet 26 may be required. It has been found, however, that for most secondary high explosives useful in well perforators the restraining force (on the order of 1,000 pounds) provided by a tight press fit of bullet 26 (which has a shank diameter on the order of one-half inch) into members 30 and 31 provides suitable release means for preventing the pressure in firing chamber 40 from building up to the point at which initial deflagration becomes detonation.

Although deflagration of explosive body 45 avoids sudden destruction of the gun as by splitting the body 12, it has been found that deflagration at too high a combustion rate may produce shock forces that cause deformation and enlargement of the barrel member 17 and other parts of the gun. This causes the performance of the gun to deteriorate substantially after only a few charges have been fired and thus shortens the useful life of the tool. In order to reduce the rate of deflagration of body 45 so that such gradual damage is minimized, a preferred embodiment of this invention includes the incorporation of a selected amount of inert material, such as talc, into explosive body 45. Where cyclonite is used as the low explosive, from about 10% to about 20% by weight of body 45 is inert material with a preferred composition being about 85% by weight cyclonite and about 15% by weight talc.

The inert component of the mixture is preferably in the form of a very finely divided powder having an average particle size smaller than that of the explosive substance. This is to permit particles of the inert material to coat the explosive particles and delay the transmission of flame between them. Although talc is the preferred inert component of the composition of this invention, any other non-combustible material that will suitably delay flame transmission may also be used.

Although this invention has been described in connection with bullet perforating guns, it will be recognized that it has applications in connection with other projectile propelling tools such as core samplers used in high temperature environments such as found within oil wells. Other applications, as well as the use of secondary high explosives, low explosives, and inert materials other than those specifically enumerated will occur to those skilled in the art and are within the purview of this invention.

I claim:

1. In a projectile propelling gun for use in a high temperature environment, formed of a gun body, means forming a firing charge chamber in the gun body, means defining a barrel bore in communication with the firing

charge chamber, a projectile slidably fitted in the barrel bore and a firing charge in the firing chamber, the improvement comprising the firing charge being formed of:

5 a body in which the propellant is exclusively secondary high explosive; and

igniting means developing sufficient energy to deflagrate the firing charge but insufficient energy to detonate it.

2. In a projectile propelling gun for use in a high temperature environment, formed of a gun body, means forming a firing charge chamber in the gun body, means defining a barrel bore in communication with the firing charge chamber, a projectile slidably fitted in the barrel bore and a firing charge in the firing chamber, the improvement comprising the firing charge being formed of:

a body in which the propellant is exclusively secondary high explosive;

igniting means developing sufficient energy to deflagrate the firing charge but insufficient energy to detonate it; and

means for maintaining the ambient pressure around said firing charge below that at which there is transition from deflagration to detonation of said firing charge.

3. The combination according to claim 2 wherein said secondary high explosive is cyclotrimethylenetrinitramine.

4. The combination according to claim 2 wherein said means for deflagrating includes black powder.

5. The combination according to claim 2 wherein inert material is interspersed with the secondary explosive in the firing charge to delay the flame transmission between the grains of the secondary explosive.

6. In a projectile propelling gun for use in a high temperature environment, the combination comprising:

means forming a firing chamber in said gun;

a body in which the propellant is comprised exclusively of secondary high explosive in said chamber;

means for deflagrating said body;

a projectile positioned as a closure for said chamber; and

restraining means holding said projectile against initial movement from its closure position, said restraining means adapted to permit movement of said projectile when the pressure within said chamber has reached a level less than at which there is transition from deflagration to detonation of said body.
